UNITED STATES PATENT OFFICE.

MAXIMILIAN WEIL, OF NEW YORK, N. Y., ASSIGNOR TO SPHINX GRAMOPHONE MOTORS, INC., OF NEW YORK, N. Y., A CORPORATION OF NEW YORK.

TURNTABLE-BRAKING MEANS.

Application filed April 3, 1919, Serial No. 237,238. Renewed October 23, 1923.

To all whom it may concern:

Be it known that I, MAXIMILIAN WEIL, a citizen of the United States of America, residing at borough of Manhattan, city, county, and State of New York, have invented certain new and useful Improvements in Turntable-Braking Means, of which the following is a specification.

This invention relates to turn tables for 10 motors and means for braking the same.

An object of the invention is to provide a turn table of a phonograph, or like device, with improved braking means for gradually retarding the speed and arranged 15 to materially reduce the stresses and strains to which the parts of the turn table and the parts of the motor are subjected. A further object of the invention is to arrange the braking means in an improved relation 20 relative to the turn table whereby the extent of wear of the engaging parts is reduced.

In accordance with the most preferred forms of my invention, the turn table is 25 provided with abutment means coacting with a yieldable retarding element, the same being arranged and constructed for retardation gradually until the turn table is brought to rest.

30 Further features and objects of the invention will be more fully understood from the following description and the accompanying drawings, in which—

Fig. 1 is a top plan view of a turn table 35 of a phonograph, with the upper surface partly broken away;

Fig. 2 is a section on line 2—2 of Fig. 1, as viewed in the direction of the indicating arrows; and

40 Fig. 3 is a front elevation of the brake stop.

In the drawings I have indicated a form of my invention applicable for braking the turn table of a phonograph, although as is 45 apparent the invention is applicable to other types of turn tables and other devices adapted to be braked.

The turn table 1 is mounted on the shaft 2, of usual construction as by means of the 50 usual recessed lug 3. The shaft 2 is driven by a spring wound motor, an electric motor or other suitable actuating means, preferably provided with a speed regulator.

55 The gradually retarding means comprises one or more members of predetermined pe-

riphery, coacting with a yieldably mounted retarding means, including a spring or other yieldable, and preferably resiliently yieldable, element. In the embodiment of the invention shown in the drawings, I have 60 indicated three members of predetermined contour, designated respectively 4, 5, 6, each formed of a strip of metal disposed on and carried by the inner side of the rim 7 of the turn table. The attachment of each 65 member 4, 5, 6 to the inner rim 7 may be performed by soldering, or by riveting or other approved means. As shown each member 4, 5, 6 is of a graduated curved contour and may, as shown, be disposed about 70 the inner face of the rim 7 to extend around the entire circumference of the inner face of the rim 7.

The yieldably mounted retarding means comprises the arm 8 provided with a braking face of leather 9 or similar friction material, said arm 8 being pivoted on the pin 10 extending from the plate 11 mounted by means of the screws 12 on a suitable support. The arm 8 is controlled by means 75 of the finger 13, for manual control, or by any of various equivalent means of familiar type automatically or manually actuated. The arm 8 is provided with the eccentrically mounted spring 14, shown 80 having its one end fixed on the pin 15 carried by the base 11 and its opposite end secured to the pin 16 disposed on the arm 8 eccentrically relative to the center of the pivot 10. 85

Accordingly, upon manually or otherwise tripping the arm 8 the brake facing of leather 9 is brought into engagement with the effective face of the retarding members 4, 5, 6 thereby providing an undulating face 90 of engagement for the facing 9. At the instant of contact of the facing 9 with any member 4, 5, 6, as for example, at the position shown in Fig. 1, assuming the turn table to have been rotated in the direction of 100 the arrow 17, the continued rotation of the turn table 1, by reason of the "trough" 18 opposite the member 6, effects a movement of the arm 8 more closely toward the inner periphery of the rim 7, thereby lessening 105 the effective lever arm of the force applied by the spring 14 to the arm 8 and accordingly applying to the facing 9 a force insufficient to instantly brake the turn table, but of sufficient force to gradually retard 110

the turn table. Upon the continued rotation of the turn table when in the direction of the arrow 17, past the point 18, see Fig. 1, the facing 9 rides on the "up" curve of the member 5, during which stage an increasing degree of retardation is exerted, and after passing the "crest" of the member 5, the degree of retardation is decreased until the retarding member 6 is reached 10 and a similar graduated retardation is effected.

In operation, my apparatus thus exerts its maximum braking force only at intervals, the braking force being applied continuously 15 in the preferred embodiment and alternately increasing to and decreasing from the maximum value. It will also be seen that the maximum braking force is applied during longer periods as the turn table slows down 20 until the motor is brought to a full stop. My braking apparatus thus eliminates the harmful strains upon the spring motor which may result from bringing the turntable to an abrupt stop.

25 Preferably, each retarding member 4, 5, 6 is an arc of a circle and in the specific instance shown, the center of the member 4 is located at the point 21, the center of the member 5 is located at the point 19 and the center of the member 6 is located at the point 20.

30 The invention is applicable similarly for phonograph turn tables of the type of externally engaging braking members; however, the type of internally engaging braking members as shown in the drawing, is advantageous by reason of its concealment and by reason of the absence of dissymmetrical parts and embodies features of simple assembly.

35 It will be noted that the invention comprises, in coaction with the yieldable braking stop, means of varying diameter or other variable contour adapted to gradually brake the turn table by the application 45 of variable braking force, tending to gradually retard the turn table and the gearing or other actuating means.

40 Whereas I have described my invention 50 by reference to specific forms thereof, it will be understood that many changes and modifications may be made without departing from the spirit of the invention as defined by the appended claims.

55 I claim.

1. In a phonograph, the combination with the turn table, of braking means for said turn table, comprising a member of varying contour controlled by said turn table, a 60 yielding element normally maintained out of engagement with the rotating parts adapted when in braking position to engage said member of varying contour, and means for supporting said yielding element.

2. In a phonograph; the combination with the turn table of braking means comprising a member of varying contour carried by said turn table, an arm, means for pivotally mounting said arm and resilient 70 means controlling said arm, said arm being arranged to engage said member of varying contour when in braking position and being normally maintained out of engagement with the rotating parts. 75

3. In a phonograph; the combination with the turn table having a circular periphery, of braking means comprising an eccentric conformation upon said circular periphery and a yieldingly mounted element 80 adapted when in braking position to engage said eccentric conformation but maintained in non-braking position during operative rotation of the turn table.

4. The combination with a rotatable turn 85 table of a phonograph having a circular periphery, of braking means therefor, comprising a plurality of serially arranged members disposed eccentrically relative to said circular periphery, a yieldable arm 90 adapted to engage said eccentrically disposed members and means for moving said arm into and out of braking position.

5. The combination with a rotatable phonograph turn table including a rim having 95 an inner circular periphery, of braking means comprising a plurality of members disposed within said rim and eccentrically relative to said circular periphery, an arm, means for pivoting said arm and means 100 for resiliently controlling said arm.

6. In a phonograph, the combination with the turn table, of braking means for said turn table comprising a member of varying diameter controlling said turn table and a 105 stop adapted when in braking position to engage said member of varying diameter and held in non-braking position during operative rotation of the turn table.

7. The combination with a rotatable, circular turn table of a phonograph, of braking means therefor comprising an element of varying diameter carried by said circular turn table, a yielding stop and means for moving said stop at will into engagement 115 with said member of varying diameter.

8. The method of bringing a phonograph spring motor to a full stop which consists in applying at intervals a braking force of a predetermined magnitude. 120

9. The method of bringing a phonograph spring motor to a full stop which consists in braking the turntable shaft with a gradually varying force alternately increasing in magnitude to and decreasing from a definite 125 maximum value.

10. The method of bringing a phonograph spring motor to a full stop which consists in applying at intervals a braking force of a predetermined magnitude, and of 130

a duration increasing as the motor is retarded.

11. The method of stopping the operation of a phonograph spring motor which consists in braking the turn table with a gradually varying force alternately increasing in magnitude to and decreasing from a definite

maximum value, while lengthening the period during which the maximum braking force is applied as the turn table is retarded **10** from operative running speed to full stop.

In testimony whereof I have signed this specification this 21st day of March 1919.

MAXIMILIAN WEIL.
